UNITED STATES PATENT OFFICE.

DAVID E. OLDS, OF NEWARK, NEW JERSEY.

MANHOLE-COVER.

SPECIFICATION forming part of Letters Patent No. 783,702, dated February 28, 1905.

Application filed June 10, 1903. Serial No. 160,855.

To all whom it may concern:

Be it known that I, DAVID E. OLDS, a citizen of the United States, residing at Newark, in the county of Essex and State of New Jersey, have invented and produced a new and original Improvement in Manhole-Covers; and I do hereby declare the following to be a full, clear, and exact description of the invention, such as will enable others skilled in the art to 10 which it appertains to make and use the same, reference being had to the accompanying drawings, and to numerals of reference marked thereon, which form a part of this specification.

15 This invention relates to certain improvements in covers for the manholes of sewers, water-mains, vault-inlets, electrical conduits, and the like, whether they be round, square, or other shape in plan, the same to be employed more particularly in connection with smooth pavements of wooden blocks, brick, asphalt, concrete, &c.; but the use of said covers is not limited to such pavements only.

20 The objects of the invention are to avoid the objectionable ring or rattle occasioned by the metallic covers when run over by a rapidly-moving vehicle, to provide a non-sonorous cover which will be durable, but inexpensive, and to obtain other advantages and 30 results, some of which will be referred to hereinafter in connection with the description of the working parts.

The invention consists in the improved manhole-cover and in the arrangements and combinations of parts of the same, all substantially as will be hereinafter set forth, and finally embraced in the clauses of the claim.

35 Referring to the accompanying drawings, in which like numerals of reference indicate corresponding parts in each of the several figures, Figure 1 is a plan of my improved cover. Fig. 2 is a section of the same, taken on line *x*. Fig. 3 is a sectional view illustrating a modification of construction, and Fig. 4 is a detail 40 section taken at line *y*.

In said drawings, 10 indicates the metal frame or body of the cover, which is preferably of malleable iron or cast-steel and is annular in plan and of one integral piece. It is 45 provided at its upper edge with an outwardly-

extending flange 11 to rest on the manhole-head (not shown) in any suitable manner. At the lower edge said frame 10 is provided with a flange 13, on which a bottom plate 12 is seated. The bottom plate may be integral 55 with the frame, as indicated in Fig. 3. The outwardly-extending flange 13 on the under side is preferably furnished with recesses 14, in which is rubber insulation or rubber cushioning material 15, adapted to prevent the production of sound or the transmission under certain conditions of electrical currents. Under certain other conditions the parts 15 may be of copper, brass, lead, or fibrous matter. The frame and its bottom plate together form 60 a pan-like receptacle for wooden blocks 16 or other non-sonorous material, which is preferably the same or similar material to that with which the street is paved. Said blocks lie at their tops flush with the top of the frame 65 and make therewith a comparatively smooth surface over which the vehicle-wheels may run. At suitable points through the body of wood are arranged ventilating tubes or pipes 17 17, which are preferably flanged at the top 70 and extend downward through perforations in the bottom plate. The last said perforations are preferably larger than the tubes or pipes to prevent a contact of said tubes with the bottom plate and the production of noise. 75 The flanges at the top of the ventilating-tube rest on the filler of wood or other material less sonorous than that of the frame 10, and as the said filler wears away the said flanges sink into the filler, the lower ends of the tube 80 sinking correspondingly through the perforations of the sheet-metal plate. Said tubes may serve to receive the bars, hooks, or other devices employed in raising the cover from the manhole, although I prefer to recess or 85 notch the peripheral flange 11, as shown at 18, to facilitate such raising. When employing a filler in the chamber of the dish-shaped receptacle of concrete or other plastic and non-sonorous material, I prefer to employ in 90 addition to the tubes, if such are employed, one or more U-shaped bolts 19, (shown in Fig. 3,) the threaded ends of which extend downward through the bottom plate and are fastened by nuts 20, or said ends may be held 95 100

by upsetting the same or by any other suitable means. Into the chamber or receptacle thus furnished the plastic matter may be pressed, so as to surround the bolt and be held 5 thereby securely in place.

I am aware that various modifications other than those described may be made in the construction of my cover without departing from the spirit and scope of the invention, and I do 10 not wish to be limited by the positive descriptive terms employed above, excepting as the state of the art may require.

Having thus described the invention, what I claim as new is—

15 1. The improved manhole-cover, comprising a frame outwardly flanged at the top and inwardly flanged at the bottom, a perforated sheet-metal plate seated on the inward flange, a filler of material less sonorous than that of said frame, and a series of tubes which ex- 20

tend both through said filler and the perforated sheet-metal plate, substantially as set forth.

2. The improved manhole-cover, comprising a frame outwardly flanged at the top and 25 inwardly flanged at the bottom, a perforated sheet-metal plate seated on the inward flange, a filler of material less sonorous than that of said frame, and a series of tubes which extend both through said filler and perforated 30 sheet-metal plate, said tubes being flanged at the top, the flanges resting on said filler, substantially as set forth.

In testimony that I claim the foregoing I have hereunto set my hand this 21st day of 35 May, 1903.

DAVID E. OLDS.
